UNITED STATES PATENT OFFICE.

PIERRE LORILLARD, JR., OF NEW YORK, N. Y.

TOBACCO-BOX.

SPECIFICATION forming part of Letters Patent No. 224,096, dated February 3, 1880.

Application filed December 23, 1879

To all whom it may concern:

Be it known that I, PIERRE LORILLARD, Jr., of New York city, in the county and State of New York, have invented certain new and useful Improvements relating to Tobacco-Boxes and analogous boxes for pocket use, of which the following is a specification.

I form the cover with one or more openings of a proper form, and mount close beneath a revolving disk carrying figures or devices, which, when the box is closed, is perfectly protected, but when the box is opened may be easily set in any required position.

To facilitate adjustment the edge of the disk may be notched to engage with the finger-nail or other object introduced to adjust it.

I propose to employ the invention to present tint-type pictures or various other devices. One may be an almanac or calendar.

The accompanying drawings form a part of this specification, and represent what I consider the best means of carrying out the invention.

Figure 1 is a face view of the top of the box in use. Fig. 2 is a central longitudinal section, and Fig. 3 is an inside view of the cover. Fig. 4 is a face view of a modification. It represents a box having but a single opening in the cover, adapted to show portraits or other devices, so as to realize some of the advantages of the invention.

Similar letters of reference indicate corresponding parts in all the figures.

A is the body of the box. B is the cover, and b the hinge, by which these parts are connected.

Referring to Figs. 1 and 3, b' and b² are apertures in the cover B, arranged at different distances from a central pivot, c, set in the cover B.

C is a disk of stiff thin metal, as sheet-iron tinned or nickelated to present a polished and tasty appearance, and engraved or otherwise prepared on one side with figures (not shown) arranged at the same distances from the center as the apertures b' b². This disk is mounted on the inner face of the cover, and may be turned on the pivot c, when the box is open,

by acting on it with pressure on its inner face applied by the finger or thumb.

The parts, being thin, do not appreciably reduce the capacity of the box, which may serve as a box for tobacco, matches, or other uses, as may be required.

Modifications may be made within wide limits in the nature of the devices carried on the disk C. Some of the advantages may be realized with only one series of holes or only one hole. I believe it possible to employ the movable piece C as a slide, not turning on a pivot, but strongly and securely mounted by other means, so as to turn or otherwise move to change the devices presented to the one or more holes in the cover.

The part C may be a rectangular or other shaped slide moved bodily to one side or the other, and firmly held by friction, with liberty to apply force to adjust it when the box is opened.

I propose in some cases to produce in the cover B another series of apertures within the series b', to serve, with suitable figures on the disk, as a game-counter.

I can, if preferred, stamp the cover by dies so formed as to slightly raise that portion of the metal immediately over the disk C.

I claim as my invention—

1. The thin movable disk or plate C, in combination with the perforated cover B of a box, and arranged to lie close on the inner face of the said cover, and to be adjusted relatively thereto by the friction of the finger or thumb, as herein specified.

2. The box A B, hinged at b, and provided with two series of holes, b' b², arranged at different distances from the central pivot, c, in combination with a thin metallic disk, C, applied close to the inner face of the cover, and adjustable around the pivot c by being turned thereon, as and adapted to serve the purposes herein specified.

P. LORILLARD, JR.
